TABLET

Donald Earl Dailey, Evansville, Ind., assignor to Mead
Johnson & Company, a corporation of Indiana

Application February 26, 1958, Serial No. 49,798

Term of patent 14 years

(Cl. D16—3)

Fig. 1.

Fig. 2.

Fig. 3.

Fig. 4.

Fig. 1 is a top perspective view of a tablet embodying my new design.

Fig. 2 is a corner elevation thereof.

Fig. 3 is a bottom view thereof.

Fig. 4 is a corner elevation thereof taken at a right angle to the elevation of Fig. 2.

The characteristic feature of my design resides in the combination of a tablet having a convex top and bottom with a flat-bottomed groove diagonally disposed on both the top and bottom, as shown.

I claim:

The ornamental design for a tablet, as shown and described.
